(57) **CLAIM**

The ornamental design for a sheet pile connector, as shown and described.

DESCRIPTION

FIG. 1 is a front, left side perspective view of a sheet pile connector showing my new design in use.

FIG. 2 is a top view thereof; and,

FIG. 3 is a rear, right side perspective view thereof.

The broken lines rendered in the drawings depict environmental subject matter intended to assist in showing how the design appears when in use and form no part of the claimed design.
